UNITED STATES PATENT OFFICE.

HENRY TIFFANY, OF NEWARK, NEW JERSEY.

HAND-BAG FASTENER.

1,143,514.

Specification of Letters Patent. Patented June 15, 1915.

Application filed December 18, 1913. Serial No. 807,431.

To all whom it may concern:

Be it known that I, HENRY TIFFANY, a citizen of the United States, and a resident of Newark, in the county of Essex and State of New Jersey, have invented a new and Improved Hand-Bag Fastener, of which the following is a full, clear, and exact description.

Among the principal objects which the present invention has in view are: To provide an auxiliary lock to maintain a handbag in closed position and to conceal the primary lock thereof; to provide means requiring forceful displacement to gain access to the primary lock; and to provide a protective misleading structure to invite attack thereon and to thereby avert attack on the primary lock.

In the drawings: Figure 1 is a perspective view of a closure frame designed for a hand bag, having applied thereto a protective lock constructed and arranged in accordance with the present invention; Fig. 2 is a top plan view of the same; Fig. 3 is a cross-section taken on the line 3—3 in Fig. 2; Fig. 4 is a perspective view, showing the frame in the bag-opened position; Fig. 5 is a cross-section taken on the line 5—5 in Fig. 2.

The hinged side frames 10 and 11 and the spring catches 12 with which said frames are provided, are of conventional form and structure. The lock formed by said frames and the catches 12 is very convenient, the action of the catches in springing past and falling behind each other, affording simple and easy means of opening by pressing the thumb and finger upon the same to force them past each other into the disengaging position. Difficulty, however, has arisen from the fact that the operation of the lock, while convenient for the owner, is also convenient to pick-pockets or thieves. Many devices have been employed to augment the lock formed by the catches 12, 12. These devices, in avoiding complication, have been equally simple of manipulation for the thief, and have afforded little, if any, protection to the person carrying the bag.

Primarily, the object of the present device is to confuse or deceive the thief, by covering the catches 12 with a hollow cap 13, which is provided with an arm 14 sufficiently long to extend away from the catches 12, to be there pivoted by a pin 15. The

length of the arm 14 is such as to permit 55 the cap 13 to settle over the catches 12, when engaged, without striking upon said catches.

The cap 13 is preferably turret-shaped, in imitation of the conventional pedestal of the conventional slide latch provided for locks 60 of this character. To further aid in this misconception, a raised portion 16 is provided, shaped to imitate in appearance the slide button of a latch of the character mentioned.

To hold the cap 13 in closed position covering the latches 12, I provide pins 17, which are fixedly mounted on the side frames 10 and 11, adjacent the latches 12, 12. To engage and pass over said pins, I 70 contract the lower edges 18 and 19 of said cap, which edges pass under said pins, to be thereafter held in position thereby.

With a protective lock thus constructed and installed on a bag having side frames 75 10 and 11, it will be found necessary, before the catches 12, 12 may be tampered with, to raise the cap 13. The grip of the lower edges 18 and 19 with the pins 17, 17 is such as to require that the frame or bag 80 be held while the cap 13 is pulled from engagement with the pins 17. Ordinarily, the force required to disengage the cap 13 from the pins 17 is such as would lift the bag to which the frame is applied.

It will also be observed that a thief or pick-pocket would ordinarily be deceived by the appearance of the cap 13, and be misled into first endeavoring to slide the raised portion 16 in the manner followed 90 90 when using a slide latch of which the cap 13 is imitative.

While I have herein described the cap 13 as solid in appearance, the design having for its purpose the imitation of the usual 95 slide latch, I do not wish to be confined to such, as the construction may be largely varied to form many different types or designs. In each, however, the concealing of the catches 12 is the dominant character- 100 100

While I have herein described the cap as being provided with an arm such as indicated by the numeral 14, I do not wish to be understood as limiting myself to the use 105 of such. It is evident that the cap may be attached on the frame by being hinged, by a chain, by a slide, and by various means not

here mentioned, all of which are considered by me as equivalents of the said arm and pivot.

I claim—

5 In combination, a plurality of side frames having a lock provided with two upstanding spring-yielding members adapted to pass and engage each other; a plurality of projecting members extending from the
10 sides of said frames; and a top covered cap adapted to infold said upstanding members,

said cap having pendant relatively contracted sides adapted to pass over and engage said projecting members.

In testimony whereof I have signed my name to this specification in the presence of two subscribing witnesses.

HENRY TIFFANY.
